UNITED STATES PATENT OFFICE.

DANIEL S. PAGE, OF MALDEN, AND JOSEPH L. BERTSCH, OF CAMBRIDGE,
ASSIGNORS TO SAID PAGE AND ALBERT N. PAGE, OF MALDEN, MASSACHUSETTS.

LANTERN FOR ELECTRIC LIGHTING.

SPECIFICATION forming part of Letters Patent No. 484,449, dated October 18, 1892.

Application filed December 12, 1891. Serial No. 414,783. (No model.)

To all whom it may concern:

Be it known that we, DANIEL S. PAGE, residing at Malden, and JOSEPH L. BERTSCH, residing at Cambridge, in the county of Middlesex, State of Massachusetts, citizens of the United States, have invented certain new and useful Improvements in Lanterns for Electric Lighting; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to lanterns, especially such as are adapted to contain electric lights and employed in marine service.

The object of our invention is to enable the lantern to be used for two different purposes and adapt it to perform such duties as usually require the services of two lanterns of distinct construction.

Briefly described, our invention consists in an ordinary lantern which is equipped with a removable shield. To the latter is attached an adjustable slide. Thus by taking off the shield an ordinary open or deck lantern is produced, while if the shield is affixed in position—an act very readily done—a battle-lantern or deck-lantern with shield is created. By means of the latter construction should the slide be drawn out the light is effectually concealed, or by withdrawing said slide it may be exposed wholly or in part, while the rays may be emitted in any direction desired by turning the lantern so as to bring the uncovered part of the lantern-globe in that direction.

The drawings accompanying this specification represent, in Figure 1, a lantern embodying our invention in elevation, shown as an ordinary open or deck lantern. Fig. 2 represents the same equipped with the shield and slide to be used as a battle-lantern or deck-lantern with shield. Fig. 3 is a perspective view of the shield and slide.

In said drawings the lantern is shown as consisting of the usual ornamental cap 2, beneath which is secured the lantern-head

proper 3, with a flange at 4. To this flange is attached the wires or rods 5, which serve to protect the lantern-globe. The latter is of a cylindrical form, closed at the bottom and open at the top. The upper extremity is exteriorly screw-threaded to engage the screw-threads formed interiorly on the lantern-head, while a gasket 7, of rubber or analogous material, is held between said globe and the lantern-head to make the interior space of said globe steam and water tight, and thereby insure the safety of the electric-light bulb. The latter at 8 is for use on an incandescent electric-light system and is removably attached to and pendent from a central tube 9, adapted to receive the conducting-wires 10. These latter are properly insulated and covered with packing or other material which shall completely fill the bore of said tube and likewise prevent the entrance of steam or water within the lantern-globe at this point. A metallic base-ring 12 of any ornamental cross-section receives the lower ends of the rods or guard-wires, thereby making the structure strong and rigid. A handle or bail 13, by which to carry the lantern or from which to support it in any suitable spot, surmounts the cap.

To render this lantern serviceable, either as an open-deck lantern (see Fig. 1) or a battle-lantern or deck-lantern with shield, as in Fig. 2, we have removably attached a pendent apertured shield 14, by means of a flange 15 to the lantern-head. This flange or lip is formed with suitable holes 16 (see Fig. 3) of sufficient size to admit the heads of the holding-screws 17, which engage in the flange of the lantern-head, while a slot 18 extends from each of said holes. These slots are of a size to receive the body of the screw. Hence in order to attach the shield to the lantern the holes are caused to register with the screws, the flange 15 is thrust over them, and a slight turn given to said shield, which causes the body of the screws to enter the slots 18. The screws are then turned home and the shield is secured in place and forms a fixed part of the lantern, being located between the lantern-globe and the outside protector-rods.

The above arrangement obviates the removal of the screws from the flange of the

lantern-head and enables the shield to be put on or taken off very quickly and easily. Inclosing the body of the shield is loosely fitted an adjustable slide 19, which is held in place 5 by the flange 15 of said shield at the top and a bead or projection 20 at the bottom. A hand-grasp 21 serves to move it circumferentially about the shield. Both the shield and its slide are sections of cylinders with co-operating openings, respectively, semicylindrical in shape, or approximately so, in order 10 that the two parts when used conjointly shall create an imperforate or closed cylinder, the edges of the slide overlapping in part the edges of the shield (see Fig. 3) to effectually 15 prevent the passage of light at the time the slide is drawn forward into an active position.

In the operation of this apparatus as a bat- 20 tle-lantern or deck-lantern with shield when the slide is drawn over the aperture which exists in the shield the light is effectually concealed. On the other hand, if the slide is drawn entirely back the full power of the 25 light is exposed, and the rays are then emitted through an arc, which may be of one hundred and eighty degrees, but the extent of which is determined by the size of the aperture in the shield as controlled by the slide. 30 The shape of the shield-aperture may be of any form desired. The rays will be cut off by the shield in the rear of the light, as in a search-light, at all times when such shield is in use. To remove the shield and slide, the 35 holding-screws 17 are relaxed. Movements the reverse of those hereinbefore described now take place, and said parts are taken off, leaving the lantern to be used as an ordinary deck-lantern. Thus it is readily understood that 40 the light, incandescent or otherwise, may be employed to emit rays in every direction or for a horizon of three hundred and sixty degrees. In the event of the addition of the

shield and slide said rays are limited from a horizon of a semicircle or one hundred and 45 eighty degrees at such time as the slide is fully open to a horizon of no degrees, or when the slide is completely closed.

What we claim is—

1. As a new article of manufacture, a lantern composed of a lantern-head, a lantern-globe, protector-rods to surround the latter, and a removable apertured shield with an adjustable slide to inclose said lantern-globe, substantially as herein set forth. 55

2. The combination, with a lantern, of a shield composed of an imperforate cylindrical apertured plate, and means whereby said shield may be detachably held in place upon the lantern, and an adjustable slide movable 60 about said shield and adapted to close said aperture in the shield, substantially as explained.

3. In combination with a flanged lantern-head, the globe removably attached thereto, 65 the packing to form a tight joint, and the exterior guard-rods, a removable apertured shield secured to said lantern-head, a slide adjustable about said shield, and a hollow tube to admit electric conductors, as herein 70 set forth and specified.

4. The combination, with a capped lantern-head, its exterior guard-wires, and annular base-ring, of a lantern-globe adapted to form a steam and water tight joint with said head, 75 an apertured shield removably affixed to the lantern-head, its movable slide, and means for operating the same, substantially as stated.

In testimony whereof we affix our signatures in presence of two witnesses.

DANIEL S. PAGE.
JOSEPH L. BERTSCH.
